COSMETIC KIT

Geraldine Bourdon, San Diego, Calif.

Application July 22, 1954, Serial No. 31,543

Term of patent 14 years

(Cl. D86—10)

The figure of the drawing is a perspective view of a cosmetic kit, with the lid open, showing containers fixed in position.

The articles shown in dotted lines are merely illustrative of articles that may be carried therein.

I claim:

The ornamental design for a cosmetic kit, as shown and described.
